UNITED STATES PATENT OFFICE.

HENRY FAIRBANKS, OF ST. JOHNSBURY, VERMONT.

MANUFACTURE OF PAILS, &c., FROM PAPER-PULP.

SPECIFICATION forming part of Letters Patent No. 396,198, dated January 15, 1889.

Application filed June 1, 1887. Serial No. 239,943. (No model.)

To all whom it may concern:

Be it known that I, HENRY FAIRBANKS, of St. Johnsbury, Caledonia county, in the State of Vermont, have invented a certain new and 5 useful Improvement in the Manufacture of Pails and Analogous Vessels from Paper-Pulp, of which the following is a specification.

I have discovered that torn edges of partially-manufactured articles of pulp, preferably that made from wood, may be strongly and neatly united by applying together and filling the interstices with fresh pulp and hardening the whole. I have devised mechanism for acting in this manner on previously-treated material and producing the required pails or other articles with great strength and uniformity. I have discovered that steam may be applied to such material, so as to greatly expedite the expulsion of the 20 water from the pulp and the drying and completion of the article.

The following is a description of what I consider the best means of carrying out the invention.

25 Figure 1 is an end elevation, Fig. 2 a side elevation, and Fig. 3 a plan view, showing the apparatus for producing the hollow frustums of cones of pulp. Fig. 4 is a plan view showing an additional feature of the apparatus 30 which is used at a certain stage of the operation; and Fig. 5 is a vertical section through the hydraulic press and accompanying parts which are used to complete the manufacture.

Similar letters of reference indicate like 35 parts in all the figures where they occur.

A is a tank containing pulp in the proper thin condition for ordinary treatment.

B is a conical roller having a surface of wire-gauze properly supported on the inside 40 to bear a moderate pressure. It is mounted on an inclined shaft, b, by which it is slowly turned by friction. The shaft is hollow and allows the easy escape of the water from the pulp as it comes in through the gauze, and thus 45 insures the rapid formation of a continuous layer of pulp in a tolerably dense but soft condition on the exterior surface of B as it rises into contact with the roller above.

C is the roller above. It may be larger or 50 smaller than B, but should be similarly tapered and connected by links C' to uprights A' on the tank A, so as to rest its weight gently and evenly on B. The roller C is cov-

ered with felt and is of such a nature that the soft pulp, after passing through the line 55 of contact between C and B, adheres to C and is carried up by the revolution of the latter.

D is a conical roll, which is peculiarly mounted and performs important functions. It is fixed on a shaft, d, which is supported in 60 a single long bearing in a swiveling-head, G', on an upright shaft, G, supported in fixed bearings A² at the side of the tank A. When the shaft G is turned in one direction, the roller D is brought into contact with the 65 roller C, and when it is turned in the other direction the roller D is moved away therefrom and turns in mid-air, so as to allow any treatment desired to the pulp which has been accumulated on its surface. The roller D is of such 70 material or so surfaced that the soft layer of pulp carried around on C tends to leave C and adhere to D so soon as they are brought into forcible contact.

I propose usually to employ iron for the 75 main body of D, with a close-fitting cover, D', of glazed hard cloth. However this may be, so soon as one layer has been applied upon D' and allowed to remain, the succeeding revolutions present a surface of pulp simply. 80 There is little difficulty in insuring that the soft coating of pulp will be continuously transferred from B to C and from C to D', and will be accumulated in successive layers 85 on the latter until the proper quantity for the main body of a pail, or whatever the article may be, is obtained upon D'.

H is a rotary cutter with a zigzag edge. It is mounted on a shaft, h, which may be held in the hands of the attendant, or may be supported in movable bearings to allow the motions required. After the roller D, with its removable cover D', has accumulated successive layers of pulp to a proper thickness, it is swung away from its contact with C and 95 is revolved independently. In this condition the zigzag edge of H is brought into contact with the cone of pulp near the small end and allowed to travel once around, correspondingly marking and partially cutting a zigzag 100 line around the cone. I prefer that the cutting-edge be not so sharp as to cut the cloth under the pulp, or even to actually cut the individual short fibers of the pulp, but only to weaken a proper line, so that it will afterward 105 easily tear along that sharply-waved line.

Next the cloth covering of the roller D is liberated, and, if necessary, drawn with force from the large toward the small end, and taken off completely from the roller and collapsed and removed from the hollow cone of pulp and again applied to the rolls, and the operation repeated—that is to say, the roller D with its fresh empty covering D', is again brought into contact with the roller C, the rollers B and C are again started, they having been stopped while the previous pail was being cut and removed, and the next cone is wound and removed, and so on indefinitely, means being employed to maintain the stock of pulp in the tank A at about the same level and consistency, and to properly care for the soft and only partially-formed cones thus produced.

The pointed extensions at the small end of the cone of pulp have now to be bent together and united to form a strong bottom. To effect this the cone of pulp is drawn carefully down upon a tapering former, J, mounted small end up and covered with fine wire-gauze at the upper end supported by strong cross-bars, as will be readily understood, and the tapering laps split into layers and softened by water are folded inward, applying their torn edges approximately together. This pail-former J, with its drain-pipe, j, is mounted upon the plunger I of a hydraulic press. A removable piece, K, which I will sometimes term a "cylinder," having its upper end cylindrical and its lower end tapered to match the exterior of the pail, is next applied over the pulp-cone and tightly pressed down thereon. Now liquid pulp is poured into K in a previously-determined quantity. The hydraulic press is worked to raise I.

L is a stout box of cylindrical form supported under the cross-piece of the press and connected by a pipe, L', and cock L² with a boiler. (Not shown.) Packing, l, makes a steam-tight joint with the interior of K when the latter is raised. The lower side of L is perforated throughout and its edge is rabbeted, as indicated. Its lower face may be covered with wire-gauze. The cylinder K is applied while I and its pail-former J are down. The thin pulp is introduced into K while down, and after the points in the bottom edge of the pulp-cone have been completely bent inward the press is worked to raise I and its load into the position shown, where it is held firmly upon the dogs O. Now steam is admitted through L' L² and pressing on the upper surface of the fluid pulp forces the water down through the perforated bottom of L. Ultimately steam flows down through the fluid and hardening pulp into what is to be the bottom of the pail. The steam soon drives down or evaporates nearly all the water remaining in the pulp, but before this is too far advanced, and while the pulp is in a just sufficiently plastic condition, the steam aiding to make it more plastic, the press I' I is worked to raise J up into strong contact with the bottom of L. The strong and nearly uniform

pressure exerted flattens and hardens the pulp, and the rabbet around the edge of the bottom of L molds a rim corresponding to 70 and forming the chine. The steam flows down through the condensed layer of pulp and completely dries it. Now, on operating the press to lower I, some steam-pressure continuing, the cone-cylinder K is left suspended on the 75 hook-dogs P and the pail-former J on emerging below brings with it a pail not only completely molded but almost dry. This is lifted off, and the pail-former J is then ready to receive another pulp-cone and again to receive the 80 cylinder K and a fresh quantity of fluid pulp, and the entire round of operations is repeated.

The provisions for operating the press I I' and for driving the several rollers may be of 85 any ordinary kind and need not be specifically described. It is important to stop the revolutions of B and C so soon as the swinging of the roller D by the partial revolution of G shall carry it out of contact and it shall 90 consequently cease to take off the thin layer of pulp from C. The roller D is driven by a gear-wheel, E, which receives a rotary motion from a constantly-revolving gear-wheel, W, turned by a belt or otherwise by any suitable 95 motive power. While the roller D is pressed against C it receives motion from E and transmits it by friction to C, which in its turn transmits a corresponding motion by friction to B. So soon as the roller D is moved 100 out of contact with C the same movement takes the teeth of its gear-wheel E out of contact with W and all the rollers stop.

I hold the roller D in yielding but strong contact with C to allow for imperfections in 105 the workmanship and for the gradually-increasing thickness of the pulp-coating accumulated on D. I attain this by means of a spring-lever, F, which is pivoted to the fixed framing at f, and pressing with strong 110 but yielding force against the extended shaft d of the roller D, is engaged with a catch or pin, a, on the framing A. This is disengaged to allow the turning of the shaft G and consequent horizontal swinging movement of D, 115 and is engaged again to commence to receive the coatings to form another cone. The lever F may be bent so as to thus serve directly against the shaft d; but I have shown it as thus acting through the intervention of a 120 bearing-box, M, turning loosely on d and provided with a hook, m, which latter receives the lever F, and prefer so to equip the machine.

I have shown a cock, b', on the extension 125 of the hollow shaft b, which may be closed, if desired, when the lever F is unlatched and the revolutions of the rollers stopped.

The cock may, if preferred, be connected with an arm extending from the vertical shaft 130 G, so as to be closed by the movement when the roller D is swung out.

Modifications may be made in many of the details without departing from the principle

or sacrificing the advantages of the invention. I can use a conical shell of sheet metal in place of cloth for the removable covering D' of the roller D, taking care to provide for col- 5 lapsing the metal shell after its removal from D. Whether cloth or metal be used, I pro- vide a thick rim or frame at the edge which applies on the large end of D to aid in ap- 10 plying the coating or covering with some force. Such, also, may aid somewhat in its removal when filled.

The press I' I may be worked by other means than hydraulic pressure.

Sheet metal perforated may be used in place 15 of the removable cloth D'.

The article formed may be dried and indi- 20 rated by the celluloid process or by dipping in hot varnish and baking.

My experiments indicate that when the 25 folded edges of the bottom are by any chance misplaced, so that they are an inch or more apart, the thin pulp flows to the perforated former into those spaces and accumulates where the water escapes most easily, so it builds up there to even thickness.

Parts of the invention can be used without the whole. I can omit the upper set of dogs, P, or even both sets, O and P. In such case I can hold up the pail-former J against the 30 pressure of the steam by the continued action of the press I' I.

I am aware that dies heated by steam have been used in the manufacture of articles from paper-pulp; but the pulp is likely to stick to 35 the dry heated surface, and I do not claim, broadly, the use of steam. (Parker, No. 348,292, dated August 31, 1886.) I am also aware that air has been used to press the fluid pulp against a perforated former, or through the 40 sheet of pulp between perforated formers, either exhausting the interior or forcing air into an inclosing-receiver, and I do not claim the apparatus used for these purposes, (Wheeler, No. 190,654, dated May 8, 1877, and Carmichael, No. 342,180, dated May 18, 1886;) but I have proved by experiment that live steam admitted to press directly on the surface of 45 fluid pulp acts more rapidly, lays the fiber more firmly, and if driven through the sheet of pulp between perforated formers works much better than air, softening and adapting it to be molded as well as leaving it nearly dry.

I claim as my invention—

55 1. That improvement in the manufacture of articles from paper-pulp that consists in admitting live steam properly confined to press directly upon the surface of fluid pulp to force the water out, lay the fiber, and keep 60 the semi-solid mass of the partly-formed ves- sel flexible while the pressing-dies are being brought into action, as herein specified.

2. The method herein described of softening and drying, in connection with shaping, 65 articles of paper-pulp by compressing me- chanically between properly-formed perforated dies and also forcing steam from one

die to the other through the article, substan- tially as herein specified.

3. The within-described method of manu- 70 facturing pails and analogous articles of pa- per-pulp by tearing partially-hardened pulp, applying the torn edges nearly together, flow- 75 ing thin pulp between and causing it to sat- urate and become incorporated with the said edges, and subsequently draining, heating, softening, and partially drying by steam and pressing the compound mass, all substantially as herein specified.

4. The bearings A² A² and vertical shaft G, 80 supported therein, said shaft having the head G', in combination with the shaft d, journaled in said head at approximate right angles to said vertical shaft G, the conical roll D, mounted on said shaft d, with its smaller end remote from 85 said head, the tank A, and rolls for supplying a coating of pulp to said conical roll D, sub- stantially as herein specified.

5. A machine for the manufacture of arti- 90 cles from paper-pulp, comprising the bearings A² A² and vertical shaft G, supported therein, said shaft having the head G', in combination with the shaft d, journaled in said head at approximate right angles to said vertical shaft G, the conical roll D, mounted on said shaft d, 95 with its smaller end remote from said head, the box M, in which the free end of said shaft d is journaled, the hook m upon said box, the tank A, standard A', and pin a upon said tank, lever F, pivoted at one end upon said standard and adapted to engage said hook and pin, for the purpose set forth, and rolls for supplying a coating of pulp to said coni- 100 cal roll D, substantially as herein specified.

6. In the manufacture of articles from pa- 105 per-pulp, the pail-former J, having a finely- perforated top to receive the truncated cone of partially-hardened pulp, in combination with the removable piece K, of which the conical lower part fits over said truncated cone 110 and the cylindrical upper part is adapted to receive a quantity of thin pulp to join the edges and form the bottom, substantially as herein specified.

7. In an apparatus for manufacturing arti- 115 cles from paper-pulp, the combination of the conical former J, having a finely-perforated top, the cylindrical box L, having finely-per- 120 forated bottom, the removable piece K, com- prising a conical lower part fitting said former and a cylindrical upper part fitting said box, 125 hooks on said cylinder K, and dogs P for engag- ing said hooks and supporting said cylinder in elevated position, for the purpose set forth, and means for forcing said former upward, substantially as herein specified.

In testimony whereof I have hereunto set my hand, at St. Johnsbury, Vermont, this 18th day of May, 1887, in the presence of two sub- scribing witnesses.

HENRY FAIRBANKS.
